UNITED STATES PATENT OFFICE.

IRA B. MALABY, OF PHILADELPHIA, PENNSYLVANIA, ASSIGNOR TO NORMAN MELLOR,
OF PHILADELPHIA, PENNSYLVANIA.

WALL-ANCHOR.

1,208,999.

Specification of Letters Patent. Patented Dec. 19, 1916.

Application filed September 25, 1914. Serial No. 863,555.

To all whom it may concern:

Be it known that I, IRA B. MALABY, a citizen of the United States, residing in Philadelphia, Pennsylvania, have invented certain Improvements in Wall-Anchors, of which the following is a specification.

One object of my invention is to provide a wall anchor of the general type described and claimed in my patent granted January 10 13th, 1914, #1,084,458, which however shall include novel means for preventing its rotation relatively to the structure in which it is mounted during the time in which a screw or collapsing tool is being operated 15 for the purpose of setting up or collapsing it.

The invention also contemplates a novel form of relatively weak side members for the wall anchor whereby they are caused to bend at certain definite points when the 20 anchor is collapsed in order that they may most advantageously engage the structure on which they are mounted.

A further object of the invention is to provide a wall anchor particularly designed 25 for use in connecting articles such as curtain supporting fixtures to sheet metal structures, such as metallic window frames, the construction being such that when collapsed its relatively weak members shall bow in such 30 a manner as to cause them to engage said sheet metal structure in the position best calculated to permanently retain the anchor in place, and that without injury to the strength of the anchor.

35 These objects and other advantageous ends I secure as hereinafter set forth, reference being had to the accompanying drawings, in which:—

Figure 1 is a perspective view of a wall 40 anchor constructed according to my invention; Fig. 2 is an inverted perspective view of the tail end of the anchor shown in Fig. 1; Fig. 3 is a plan showing the anchor as inserted in a properly formed hole in a body 45 of sheet metal; Fig. 4 is a side elevation illustrating the wall anchor in its collapsed position with a holding screw mounted therein, and Figs. 5 and 6 are fragmentary perspective views illustrating special forms 50 of my invention.

In the above drawings 1 and 2 respectively represent the annular head and tail portions of a fastener or wall anchor and these parts are connected by any suitable 55 number (in the present case three) laterally

weak members 4 which are outwardly bowed at a point approximately one-third of the distance from the head toward the tail portion. Said portions 1 and 2 each consists of an annular structure which while it may be made in split form with its ends 16 slightly separated and diverging, is preferably continuous, said ends being brazed or welded, or mechanically connected as shown in Figs. 5 and 6.

In addition the head portion 1 has two, oppositely extending wing portions 3 formed by pressing out a pair of tongues from the top edge portion of said head so that they both extend in the same plane. The tail portion has connected to its lower edge a ring 5 of helical form which lies immediately adjacent the lower edge of said portion.

In that form of the invention shown in Fig. 5 one of the ends of either or both of the parts 1 or 2 is provided with a dovetail recess and the other with a similarly formed projection 12 fitting said recess so that said ends are effectually held from separation. 80 In Fig. 6 the two ends of the portion 2 are shown as each having a laterally projecting lug 13 while the helical ring 5 is made with an edge recess into which both of said lugs fit.

The wall anchor above described is particularly designed for connecting rigidly together two parallel bodies of thin material such as sheet metal, though obviously it may be used for other purposes, and in practice I prepare the supporting body of material 90 for reception of the anchor by forming in it a circular hole 6 and at two opposite points of said hole, cutting recesses by pressing out tongues 7 which project with their upper surfaces a definite distance below the under 95 surface of said body of metal 8. The diameter of the hole 6 is such that it will permit of passage through it of the tail portion 2 and the side members 4 of the wall anchor, as well as the head 1, except for the fact 100 that the wings 3 of said head fit into the recesses 9 from which the tongues 7 are pressed and are supported by the latter in such positions that their upper edges as well as the top edge of the head 1 are substantially 105 flush with the top surface of the body of material 8.

The wall anchor is thus firmly supported so that it extends in a line substantially at right angles to the plane of the sheet mate- 110

rial 8 and by suitable means, such as the tool described and claimed in my patent aforesaid, it may be collapsed so that its various parts occupy the relative positions shown in Fig. 4. In this collapsing operation the laterally weak side members 4, which as shown, are so made as to bow outwardly adjacent their upper ends, are bent upon themselves in such manner that they are inclined upwardly toward the under surface of the material 8 and by reason of the initial bend originally given them finally make point contact with it as shown in Fig. 4, so that they are in the best possible position to withstand an outward pull on the helical part 5.

Obviously the anchor can not fall out of the sheet material 8 since its wings 3 are held by the tongues 7 from passing through the opening therein, while the bent side members 4 prevent withdrawal in the opposite direction. The anchor is thus in the form of a socket for the reception of a screw or bolt 10 which may be passed through it and threaded into its helical member 5 so as to rigidly connect any desired structure such as the sheet metal fixture 11 to the body 8. The wall anchor above described is made of a single integral piece of sheet metal properly stamped, rolled up and formed, being made of some structurally strong material such as steel, having the necessary properties to permit of its manufacture and use without fracture or weakening.

35 I claim;—

1. A wall anchor consisting of annular head and tail sections; laterally weak members connecting said sections; and a plurality of oppositely placed wings projecting from the head section in planes substantially parallel to the axis of the anchor.

2. A wall anchor consisting of annular head and tail sections; laterally weak members connecting said sections; with a plurality of tongues bent out of the side parts of the head section and projecting in opposite directions in substantially the same straight line, said tongues lying in planes substantially parallel to the axis of the anchor.

50 3. The combination of a body of sheet material having a hole provided with two oppositely formed recesses and tongues projecting under said recesses; with a wall anchor extending through said hole and in-

cluding oppositely extending wings entering 55 the recesses and supported on the tongues.

4. The combination of a body of sheet material having a hole provided with two oppositely formed recesses and tongues projecting under said recesses; with a wall anchor 60 having head and tail sections, a screw receiving section, with members connecting the head and tail sections and bent to extend in flattened U-form at an angle to the axis of the anchor, into engagement with 65 the underside of said body of sheet material.

5. The combination of a body of sheet material having a hole provided with two oppositely formed recesses and tongues projecting under said recesses; with a wall anchor 70 having head and tail sections, a screw receiving section, and members connecting the head and tail sections and bent to extend in flattened U-form at an angle to the axis of the anchor into engagement with the underside 75 of said body of sheet material; with laterally projecting wings from the head section of the wall anchor extending within the recesses of the sheet material and prevented by the tongues from passing through the 80 same.

6. A wall anchor consisting of split annular head and tail sections of which at least one has its ends permanently connected; with laterally weak members connecting 85 said sections.

7. A wall anchor consisting of annular head and tail sections of which the latter is split and has lugs projecting adjacent its 90 ends; with a ring attached to said tail section and recessed for the reception of the lugs thereof.

8. A wall anchor consisting of annular head and tail sections of which the latter is split and has lugs projecting adjacent its 95 ends; with an integral helical ring attached to said tail section and having recesses for the reception of said lugs whereby the ends of the tail section are held together.

100 In testimony whereof, I have signed my name to this specification, in the presence of two subscribing witnesses.

IRA B. MALABY.
